United States Patent Office.

THOMAS R. HERD, OF ALLEGHENY, PENNSYLVANIA.

Letters Patent No. 98,377, dated December 28, 1869.

IMPROVEMENT IN CAR-COUPLING.

The Schedule referred to in these Letters Patent and making part of the same.

To all whom it may concern:

Be it known that I, THOMAS R. HERD, of Allegheny, in the county of Allegheny, and State of Pennsylvania, have invented certain new and useful Improvements in Car-Couplings; and I do hereby declare that the following is a full, clear, and exact description thereof, reference being had to the accompanying drawings, and to the letters of reference marked thereon, which form a part of this specification.

The nature of my invention consists in the construction and use of devices, whereby railroad or other cars can be coupled together automatically, as hereinafter fully described—

In the accompanying drawings—

Figure 1 is a section of my invention.

Figures 2 and 3, views of some of the devices used.

Letters of reference denote parts.

The body of the bumper A is hollow, and of the same construction as those ordinarily in use.

A carriage, A¹, supported by ordinary friction-rollers, A², rests on the lower portion of the internal part of said bumper, said carriage A¹ being provided at the one extremity with an ordinary geared rack, A³, projecting therefrom in such a manner that an ordinary geared pinion, A⁴, attached to a vertical shaft, A⁵, will engage the teeth of said rack A³, and by the revolution of said shaft A⁵, said rack A³ and carriage A¹ will be forced forward or backward, as required.

Said shaft A⁵ passes through said bumper A, and is provided with an ordinary ratchet-wheel, A⁶.

Pivoted to said bumper A is an ordinary pawl, A⁷, in such a manner that its point will, if required, engage the teeth of said wheel A⁶, preventing said shaft A⁵ from revolving.

Said carriage A¹ is furthermore provided at its upper portion with friction-rollers B, on which rests, when the bumpers are coupled, a curved cone, B¹, having a flat base, resting on before-named rollers B.

Said cone B¹ has a groove B² around its periphery, near to its base, said groove being encircled with the ordinary coupling-link B³.

The upper part of said cone passes upward into a curved recess, B⁴, on the upper part of the body of said bumper A, the whole being so arranged that by the moving backward of the carriage A¹, the link B³ and cone B¹ fall out of place.

By pushing forward said carriage A¹, the cone B¹ is kept in place, carrying with it the link B³, which is prevented from being withdrawn by the cone B¹ pressing against the recess B⁴.

Said bumper A is furthermore provided with a recess, C, inside of which is an ordinary curved spring, C¹, so arranged that when the link B³ is forced into said recess C, said spring C¹ holds said link B³ in position for coupling.

The bumper E is constructed hollow, and of the same material as those ordinarily in use.

Curved springs E¹ E² are attached to the inner side of the bull-head B³, in such a manner as they will penetrate through suitable slots, E¹, in the sides of said bumper E, and meet at or near the centre thereof, their upper portions being provided with seats F, so arranged that the ordinary coupling-pin G may rest thereon.

Said springs are furthermore provided with vertical rollers G¹, one to each, said rollers being situated at or near the part of said springs, opposite to the mouth of said bumper E; the whole being so relatively arranged that the link B³, being held in place by the cone B¹, and pushed against the springs E¹ E², will force apart the same; the pin G, being then unsupported, falls through the link B³, and couples together both the bumpers.

Having thus described my invention,

What I claim as new, and desire to secure by Letters Patent, is—

1. The carriage A¹, rollers A² B, rack A³, shaft A⁵, pinion A⁴, ratchet A⁶, and pawl A⁷, in combination with the curved cone B¹, link B³, spring C¹, and bumper A, having recesses B⁴ and C, when constructed, arranged, and operating substantially as and for the purpose described and set forth.

2. The arrangement of the above devices, in combination with the bumper E, springs E¹ E², seat F, rollers G¹, and pin G, when constructed and arranged and operating substantially as described, and for the purpose set forth.

In testimony that I claim the foregoing as my own, I affix my signature, in presence of two witnesses.

THOS. R. HERD.

Witnesses:

PERCEVAL BECKETT,
BENJAMIN FALLOWS.
